UNITED STATES PATENT OFFICE.

WILLIAM J. WRIGHT, OF COOPERSTOWN, PENNSYLVANIA.

STAVE JOINTING AND PLANING MACHINE.

SPECIFICATION forming part of Letters Patent No. 398,993, dated March 5, 1889.

Application filed September 25, 1888. Serial No. 286,389. (No model.)

To all whom it may concern:

Be it known that I, WILLIAM J. WRIGHT, residing at Cooperstown, in the county of Venango and State of Pennsylvania, have invented certain new and useful Improvements 5 in Stave Jointing and Planing Machines, of which the following is a specification.

My invention has for its object to provide a stave-making machine wherein the billet 10 passes through the various stages necessary to complete the stave, and, as it progresses, automatically controls and sets the cutting devices so as cut both the bevel and form the bilge of the stave in exact proportion in relation to the width of the billet.

To this end my invention consists of certain novel combinations and arrangements of mechanical devices, as will be hereinafter fully described, and be particularly pointed 20 out in the claims, reference being had to the accompanying drawings, in which—

Figure 1 is a top plan view of my machine. Fig. 2 is a vertical longitudinal section thereof, taken on the line 2 2, Fig. 1. Fig. 2^a is a similar view of the central portion of the machine. Fig. 3 is a transverse section of the same, taken on the line 3 3, Fig. 1. Fig. 4 is a similar view of the same on the line 4 4, Fig. 1. Fig. 5 is a detail perspective view of one of the head-block devices and its operative connection 30 with the main portion of the machine. Fig. 6 is a detail perspective view of a portion of the head-block J and its adjustable connection with the arm I. Fig. 7 is a detail view of the upper bearing of one of the cutter-shafts. Fig. 8 is a detail plan view of the swinging frame M, pivoted arms Q' Q', and the diagonal disks P P; and Fig. 9 is a longitudinal section of one of the head-blocks.

40 I shall first proceed to describe in a general way the main features of my invention, the operation thereof, and then specifically point out and describe the different parts in detail and point out their operative connection with each other.

45 In the practical construction of my improvement I support in the top of the main frame of the machine a series of feed-rollers which may be suitably connected with and 50 operated by the driving-gear mechanism. These rollers are so arranged in relation to the bed of the machine that one set—the lower—

will be disposed with their upper peripheral surfaces slightly above said bed, while the upper set will have a yielding bearing in the frame 55 and be arranged above the lower set. Near the forward or receiving end of the machine are arranged the trimming-saws, which are adjustably connected to the frame and adapted to be adjusted to or from each other to adapt 60 them to form staves of greater or less width, which saws operate to trim the uneven edges of the staves. A tripping device is arranged in the bed of the machine between the saws, which is arranged to be operated by the moving 65 billet in such a manner as to close the billet-entrance to said saws, and thereby prevent the insertion of a second billet before the saws have completely operated upon a preceding billet.

70 The forward upper portions of the frame and the feed-rolls are so constructed as to permit of the ready discharge to the sides of the machine of the waste stuff which is cut from the billet by the trimming-saws. The billet 75 after leaving the trimmer-saws passes along through several feed-rolls until it enters between a series of vertical guide-rollers arranged about centrally of the machine, which have a peculiar connection with two rock-shafts journaled in the main frame beneath the said bed. The billet or stave passing between the vertical rollers forces them apart, which movement rotates the rock-shafts to a certain degree, which rock-shafts also have a 80 novel connection with movable head-blocks, to which head-blocks are journaled the upper ends of the cutter-disk shafts, the lower ends, of the same being pivotally journaled in the frame. The lower ends of the shafts upon 85 which the vertical rollers are mounted are journaled in the frame and said shafts are rotated by a belt driven from the driving-pulley.

90 Certain automatically-operated mechanism 95 is connected with the head-blocks, all of which are caused to operate in a peculiar manner through the medium of the stave-billet operating upon the vertical rollers and the rock-shafts and a yielding roller, X, supported 100 above and adjacent to the rear set of the vertical rollers, whereby the cutter-disks are so moved inwardly and outwardly in relation to the moving billet, and whereby the said ent-

ters will accurately cut the bevel and form the bilge of the stave, said automatic movement of the cutters being adapted to operate upon billets of different widths. The billet 5 after leaving the cutters passes through succeeding feed-rollers to a planing-cylinder, which finishes the outer or convex side of the stave, from whence it passes out of the machine.

10 Having thus generally outlined the construction of the machine, I will now proceed to describe each part in detail and point out its operation. To make such description as clear as possible, I shall begin it at that part 15 of the machine where the billet is first entered and describe the succeeding parts as near as possible during the course of the travel of said billet.

In the accompanying drawings, A A denote 20 the main frame of the machine, which supports the table B, the forward portion of which is sloping from the center to its sides, as at b b, while its remaining portion has a curvilinear form, as at b', the table being so formed 25 as to permit of the ready discharge of the chips, splinters, dust, &c., to the sides of the machine. Below the table and projecting through proper openings formed in a central line therein are a series of feed-rollers, a, having 30 flat peripheral faces mounted upon shafts a', which have bearings in the beams a² of the frame A.

Arranged immediately above each of the rollers a and mounted upon shafts b², having 35 yielding bearings in the frame above the table B, are a series of concave-faced rollers, b³, which are preferably twice as long as the rollers a. To the forward end of the frame A is arranged the feed-platform A', which is provided 40 with a series of guide-marks, 1 1, to assist the operator in properly guiding the billets to the first set of feed-rollers. To the front end of the machine, preferably between the first and second set of feed-rollers, a transverse shaft, c, is journaled in the sides of the frame above the table, and upon which shaft are mounted the trimmer-saws C. These saws are arranged one to each side of the central part of the table and are adapted to slide to 45 and from each other upon said shaft. This adjustment of the saws is accomplished by a lever, 2 2, pivoted to the frame, as at 3, which is connected to toggle-arms 4 4, which are pivoted to longitudinal arms 5 5, pivoted at their 50 rear ends to the frame at 6 6, while their other ends are connected to collars or hubs C', formed on the saws C. Thus it will be seen that the saws may be readily thrown to or from each other by operating the handle-bar 55 7, and thus adapt the saws to trim billets of different widths. Arranged in an opening, d, in the bed B between the saws C is a swinging-stop, D. This stop consists of a spring-plate pivoted at the rear of its center, as at d', and is provided with an upwardly-projecting lip, d², at its front end, the upper edge of 60 which normally is flush with the table B, and

an inclined lip, d³, at its rear end, which projects above the plane of the table-top. By this construction it will be seen that when a billet is passed between the saws its forward end will depress the lip d³ and exert a tension upon the plate D. Now, as soon as the rear end of the billet passes the lip d² it (the lip) will fly upward and project in the line of the billet-path and prevent a succeeding billet from entering between the saws until after the first billet passes the lip d³, which allows the plate D to drop into its normal position. This operation also "times" the billets properly and prevents their crowding each other at the cutter-heads hereinafter referred to. The billet after leaving the saws is fed forward and enters between a series of vertical guide-rollers, E E E' E', mounted upon the upper ends of vertical shafts E² E², the lower ends of which are journaled in pivotal bearing-boxes e e, mounted in the main frame. Near the upper ends of said shafts E² they are provided with laterally-extending rods E³ E³, 90 which project through openings in the side bars of the frame.

The shafts E² are each provided with a sprocket-wheel, e², which are connected by a sprocket-chain, e¹, as shown.

The speed of the rollers E E' and the shafts E² is governed by the speed of the passing billet.

To each of the rods E³ E³ are connected the upper ends of stout spring-bars F F, the lower ends of which are fixed upon rock-shafts G G', mounted in the frame.

It will be observed that the vertical rollers are formed in sets—two to each side of the machine—each set and its connections adapted to operate one of the cutter-disks, and as their operation and construction are similar I shall only describe one set and its connections with the disk it operates.

Between the side beams, A', of the frame and the connection of bars F, I arrange a coiled spring, H, upon the rods E³, which will press the rollers E E' back to their normal position when the pressure exerted by the stave-billet is released therefrom. Upon one end of the rock-shaft G is secured the lower end of an arm, I, the upper end of which is adjustably connected to the upper section, J', of the movable cutter-head block J, which automatically presses the cutter-disk to or from the stave-billet.

By reference to Fig. 6 the adjustable connection of the said arm is clearly shown, the same consisting of a cross-bar, i, mounted near the end of the bar I, which bar i travels upon small vertical screw-rods secured to the section J', and which bar may be adjusted upon such rods by the jam-nuts i' i².

The head-block J, which is shown in detail in Fig. 9, is arranged transversely in the frame, and is formed of the upper and lower sections, J' J², the upper section arranged between slideways in the frame.

Arranged in front of the head-block J is

the cutter-disk shaft L, the lower end of which has a pivotal bearing, l, in the frame, while its upper end is journaled in a pivotal bearing, l', (see Fig. 7,) in an arm, l², extended upwardly from the inner end, j, of the section J'. The cutter-disk shaft is also provided with a pulley, l⁴, over which the driving-belt passes. The lower face of the upper section is provided with a series of fine rack-teeth, j³, the purpose of which will presently appear. By this construction it will be seen that when the billet enters between the rollers E'E'E'E it forces them apart, which movement of the rollers E'E' causes the rod E³ to press the spring-arms F outward and partially rock the shaft G, which movement of the shaft will, through the arm I, move the section J' outward and carry in the same direction the upper end of the cutter-shaft disk. The movement of the head-block J' moves the cutter-disks to a proper position as to the width of the stave to be formed. This relation is controlled by diminishing or increasing the radius through which the bar I moves by means of its adjustable connection with said block J'. Thus the cutter-heads are set automatically by the progress of the stave at the proper width and at the proper angle to cut the bevel of the edge.

Between the rear pair of guide-rollers, E'E', and the cutter-heads one of the upper feed-rollers, X, is mounted in upward-yielding bearings k, and it is provided with a cog-gear, k', on one end of its shaft, which shaft and roller is raised when the billet passes under them. When the said shaft is raised, its cog k' meshes with a cog, k², mounted in the frame, which cog is geared through medium of the "idler-cogs" k³, with a cog-wheel, k⁵, on a shaft, k⁶, mounted in pivoted frame M, arranged beneath the table, the construction of which will presently be described.

Depending from the shaft X are arms N, the lower ends of which are rigidly connected to a frame, O, disposed below the lower section, J², of the head-block J, said block resting upon friction-rollers n n, journaled in the frame O, said section J² being provided with a fine mesh of teeth, j³, in its upper face, for a purpose presently explained.

From the upper face of the upper sections, J', project short pintles 10, which enter diagonal slots 11, formed in the arms 12 of a bell-crank lever, 13, pivoted at 14 to the frame. Arms 15, pivoted at one end to the bell-crank-lever arms 16, are pivotally connected at their lower ends to one end of the arms m m of the frame M, previously referred to, said arms being pivoted at their opposite ends to the frame, as at m'.

As before stated, the shaft k⁶ is mounted in the frame M and carries a cog-wheel for operating it. It is also provided with two diagonally-arranged cams or disks, P P, which operate within two yokes, Q Q, formed on the ends of arms Q' Q', pivoted, as at q, to the frame and passing one under each of the head-

blocks, as shown. The arms Q' are arranged to be vibrated horizontally by means of the disks P P: Each of these bars is provided with a bearing-box, p p, to receive a projecting stud, p', secured to the under side of each of the lower head-blocks, J², for a purpose presently described.

Within each of the yokes Q Q project two screw-pins, 18 18, the ends of which are designed to abut or lightly touch the diagonal disks, against which the said disks in their rotation act as eccentrics. (See Fig. 8.)

The operation of the machine as the billet passes through the vertical or guide rolls is as follows: When the billet is about to enter between said rollers, the shafts of which rollers have a pivotal connection at their lower end, their upper ends are spread apart, the degree of such movement depending upon the width of the billet. This movement is communicated through the spring-arms, the rocks-shafts G, and the arms I to the upper head-block sections, J', which have journaled thereto the upper end of the cutter-disk shafts, said shafts swinging in an arc from their lower pivotal bearings, thus setting the disks ready to cut at a proper position for the width of the billet to be treated. This transverse movement of the upper section, J', causes the pintle 10 to operate upon the bell-crank lever 13 and cause it to slightly raise the swinging frame M, carrying the diagonally-arranged disks, and properly sets them for operation in the yokes Q. The degree which the said frame M is raised is also determined by the size of the billet. Now at this stage of treatment of the billet it will be observed that the cutter-disks which cut the bevel and the diagonal disks which regulate the bilge of the stave are properly set for operation. The billet then passes under the yielding roller, raises it and the shaft, also raises the lower head-block sections, J², into contact with the upper sections, J', by means of the rods N, and at the same time causing its gear k' to mesh with the gear k², and through the intermediate gearing cause the shaft k⁶ to revolve. It will be understood that the intermediate gearing is so arranged that but one complete turn of the shaft k⁶ will be accomplished during the passage of the length of the billet past the cutters. The cutters now begin to cut the bevel, the proper angle having been given by the movement outward of the upper head-block, J'.

Now as the billet proceeds the gearing devices from the yielding shaft to the shaft k⁶ revolve said shaft k⁶. The diagonal disks operate upon the vibrating arms, their first movement being gradually outward, which arms move both the head-block and the cutters in a similar direction and until the center of the billet is reached, when the diagonal disks begin to slowly draw the arms together and cause the head-blocks and the cutters to have a similar movement, and thereby, while the cutters are making the bevel-cut, also form the bilge at the same time,

said operation of cutting the bevel and making the bilge being done automatically and by a continuous movement of the billet. To prevent the shaft k^6 from getting a slightly 5 too much turn, which might be caused by the momentum thereof, I provide it with a ratchet-wheel, 19, and engage the same with a pawl, 20, which pawl is connected to the shaft X, as shown. By this construction it will be seen 10 that when the passing stave raises said shaft it will draw the pawl 20 out of engagement with said wheel 19, and when the end of the billet passes beyond the small roller r^3 the shaft X drops and the pawl will again drop 15 into the wheel, as will be clearly understood from the drawings. To keep the yielding shaft and roller raised after the rear end of the billet has passed from under them until it has been entirely treated by the cutters, I ar- 20 range a pivoted frame, R, which is pivoted near one end at r and has its short arms $r' r'$ extend under said shaft, while its heavier longer arms, r^2 , extend forward and form a bail on which is journaled a small friction- 25 roller, r^3 . It will be seen that as the billet passes over the roller r^3 it will hold said end down, and the arms $r' r'$ will support the shaft until the billet passes from the roller r^3 , which roller is in line with the cutters. The billet 30 passes forward and is passed beneath a concave-faced planer or cutter, which gives form and finish to the outer convex surface of the stave. It will be understood that the connection between the gear on the shaft k^6 and the 35 intermediate gear is such as to permit of the slight raising or lowering of said shaft without disconnecting said gears. As the contact-surfaces of the upper and lower sections, J' and J^2 , of the head-block J must be such as 40 to permit said sections to mesh at very short intervals of movement, I form the teeth $j^3 j^3$ of thin steel-like blades 26, (see Fig. 9,) and set them edgewise in a socket, 27, in the faces of the sections $J' J^2$ and hold them in place 45 by screws 28 and nuts 29, so they may be readily removed for grinding and any wear compensated for by placing beneath them a thin sheet of metal or other desired material. (See Fig. 9.)

50 From the foregoing description, taken in connection with the drawings, the operation and advantages will be readily understood.

Having thus described my invention, what I claim, and desire to secure by Letters Patent, is—

55 1. The combination, with the vertical guide-rollers mounted upon shafts having a pivotal bearing at their lower ends, and rock-shafts connected with said guide-rollers, of the head-blocks J, connected to said shafts and the cutter-heads, the shafts of said heads having a pivotal bearing at their lower ends in the frame, and their upper ends journaled to the head-blocks, whereby the movement of the 60 guide-rollers will automatically set the cutters to the point of the beginning of the cut

of the stave-bevel, substantially as and for the purpose specified.

2. In a stave-jointing machine, the combination, with the guide-rollers E E, mounted upon rotatable shafts having a pivotal bearing at their lower ends, rock-shafts G, mounted in the frame, arms F, connecting said shafts to the roller-shafts, and an arm, I, connected to the rock-shaft, of the head-blocks J, adapted to lateral movement in the frame, said head-blocks connected to the arm I, and the cutter-heads L, journaled at their upper ends in the head-blocks, their lower ends having a pivotal bearing in the frame, all arranged substantially as and for the purpose set forth.

3. In a stave-jointing machine, the combination of the vertical guide-rollers mounted on a shaft having a rotatable and swinging movement, rock-shafts journaled in the frame and operated by the movement of the guide-roller shafts, the divided head-blocks, the upper sections, J' , connected with the rock-shafts, the cutter-heads mounted in said sections, the yielding shaft and roller X, journaled in the frame above the bed, said shaft connected to the lower section, J^2 , said shaft X adapted to raise said lower section in operative contact with the upper section when raised, and the automatic devices, substantially as shown and 95 described, for vibrating said head-blocks, the movement of said vibrating devices, the yielding shafts, and the head-blocks being timed and regulated by the moving billet, substantially as described.

4. In a stave-jointing machine, the combination, with the yielding guide-roller shafts, said shafts journaled at their lower ends in pivotal bearings, lateral arms E^3 , connected to said shafts, said arms projected at their inner ends in the frame, and rebounding springs mounted on said arms between the frame and the roller-shafts, of the rock-shafts G, mounted in the frame-shaft, provided with arms F F, connected at their upper ends to the arms E^3 , and an arm, I, connected to the upper head-block, said head-block supporting the upper end of the cutter-disk shaft, the lower end of said shaft having a pivotal bearing at its lower end, all arranged substantially as and for the purpose specified.

5. In a stave-jointing machine, essentially as described, the combination, with the automatic feed devices, substantially as shown and described, and pivotal bearings l' , mounted thereon, of the cutter-shafts L, journaled at their upper ends in said pivotal bearings l' , and their lower ends provided with pivotal bearings e , journaled in the main frame, whereby the upper ends of said cutter-shafts will be moved differentially to determine the cut of the bevel and the bilge, substantially as shown and described.

6. In a stave-jointing machine, the combination, with the yielding roller-shafts, the rock-shafts G, operated thereby, the head-blocks J, and the cutting devices, substan-

tially as shown, connected to and operated by the head-blocks, of the adjustable connections between said head-blocks and rock-shafts, said connections consisting of arms I, secured 5 at their lower ends to the said shafts, vertically-adjustable centrally-apertured plates guided at their ends on vertical screw-posts secured at the inner ends of the head-blocks, and adjusting-nuts engaging said posts, the 10 upper ends of said arms I passed through the apertured plates, substantially as set forth.

7. In a stave-jointing machine, the combination, with the upper head-block sections, said sections connected with the cutter-disks, 15 and the yielding guide-rollers, whereby said head-blocks and cutter-disks are forced outward when the staves enter between said roller, of the yielding roller-shaft X, supported above the bed of the machine, the lower section, J², supported on the frame O, connected 20 with and operated by the vertical movement of said shaft X, and the vibrating levers arranged to be automatically operated by said shaft X and the upper head-block, whereby 25 said head-blocks are moved to and from each other to determine the curvature of the edges of the staves, as set forth.

8. In a stave-jointing machine, the combination, with the table B, having an opening, 30 d, and the trimmer-saws C C, adjustably mounted on the shaft c, supported above said bed and opening d, of the stop-plate D, pivoted in said opening, said stop adapted to automatically close the feed-passage between 35 said saws by pressure of the billet being treated, substantially as shown and described.

9. In a stave-jointing machine, the combination, with the head-blocks J, the rock-shafts G, connected therewith, spring-arms F, con-

nected with the rock-shaft, and the yielding 40 roller-shafts connected with the arms F, and the swinging frame M, of the bell-crank levers 13, provided with diagonally-slotted arms 12, adapted to receive pintles 10 on the upper sections, J', of the head-blocks, said levers pivoted at 14 to the frame of the machine and having arms 16, and arms m m, secured at 45 their lower ends to the swinging frame M and pivotally connected with the arms 16 at their upper ends, all arranged substantially as and 50 for the purpose described.

10. The combination of the swinging frame M, connected at its free end to the upper section, J', of the head-block, the shaft k⁶, journaled in said frame and provided with diagonally-arranged cam-disks P P, said shaft provided with a drive-gear, k⁵, the vibrating arms Q' Q', having yokes Q at their forward ends, their rear ends pivoted to the frame at q, said yokes formed with contact-points against 60 which the disks P operate, the yielding shaft and roller X, journaled above the bed of the machine, said shaft provided with a gear, k', which is automatically geared with the gear k⁶ on shaft k⁵, all arranged substantially as 65 and for the purpose described.

11. In a stave-jointing machine, the combination, with the shaft k⁶, having a ratchet-wheel, 19, and the shaft X, of the retaining-pawl 20, engaging the wheel 19, and a connection between said pawl and the shaft X, where 70 by the pawl is automatically lifted from engagement with the wheel 19, substantially as and for the purpose specified.

WM. J. WRIGHT.
